UNITED STATES PATENT OFFICE

JULIUS WEINBERGER, OF NEW YORK, N. Y., ASSIGNOR TO RADIO CORPORATION OF AMERICA, A CORPORATION OF DELAWARE

PAPER ROLL PHONOGRAPH RECORD

Application filed October 27, 1925. Serial No. 65,131.

The invention concerns phonograph records and a process of making them and has for its principal object to provide a non-breakable record of unlimited playing time.

5 A further object of the invention is to provide a phonograph record consisting of a roll of paper or other flexible material on which representations of the sound waves to be reproduced are printed.

10 Still another object of the invention is to provide a phonograph record consisting of a roll of paper or other flexible material on which representations of the sound waves to be reproduced are printed by first converting the sound waves into correspondingly modulated high frequency currents and recording the current fluctuations in graphical form.

15 The great majority of phonograph records made up to the present time consist of wax discs or cylinders on whose surfaces are engraved grooves having indentations or undulations corresponding to the recorded sounds. The indentations may be either 20 lateral or normal to the face of the record and serve to cause vibrations in a reproducing stylus following the grooves of frequencies corresponding to those of the original sounds. The vibrations of the stylus are 25 transferred to a mechanical vibrating member, usually a diaphragm, which thereupon sets up sound waves of substantially the same frequency and intensity as those originally recorded on the record. There are 30 numerous objections to these records. In the first place the process of manufacture is very expensive. Moreover the records are easily 35 broken and their playing time is extremely limited, about four or five minutes being the 40 maximum playing time which has been found practicable.

I propose to decrease the cost of manufacture, indefinitely increase the playing time and provide a non-breakable record by 45 registering markings corresponding to the sound waves to be reproduced on a paper roll. Replicas of the original record can then be made by ordinary printing or photographic processes and the original sounds reproduced 50 by photo-electric methods or by the use of

heat waves transmitted through or reflected from the printing on the paper. The master record under this system can be made in a number of ways. Electrical high frequency oscillations may be modulated in accordance with the sound waves to be recorded and a photographic representation of the modulated high frequency oscillations obtained by means of an oscillograph, or an engraving of the modulated oscillations may be obtained by means of an electro-magnetic, piezo-electrical crystal or condenser recorder. Again the sound waves may be recorded photographically by purely optical processes such as varying the intensity or size of a 55 shaft of light falling upon a moving strip of paper having a sensitized surface. Whatever method is used the completed record will be in the form of a roll of paper or other flexible material which will be practically unbreakable and which can be made 60 as long as desired.

65 The invention in several different forms is illustrated by way of example in the accompanying drawing in which,

70 Figs. 1 and 2 show two modifications of the process making use of modulated high frequency oscillations and

75 Fig. 3 shows a portion of a record roll made according to the invention.

80 Referring to Fig. 1 of the drawing a vacuum tube is indicated at 4 which may be arranged in any suitable manner for generating high frequency oscillations. Sound waves to be recorded are impressed on the device 1 for conversion into variable electric currents. The device 1 is coupled to the grid filament circuit of the oscillator 4 by means of the transformer 3 and a battery 2 is provided in the circuit of the device 1 to supply 85 the necessary electrical energy. The current variations resulting from the operation of the device 1 by the sound waves are thus transferred to the input circuit of the oscillator 4 and serve to modulate the high frequency oscillations generated by the oscillator. The output circuit of the oscillator contains a source of energy 5 and an inductance 6 and an oscillograph 7 is connected 90 across the terminals of the inductance 6. The 95 100

voltage drop across the inductance 6 will be proportional to the modulated high frequency oscillations generated by the oscillator 4 and these voltage drops will be impressed on the operating mechanism of the oscillograph. A photographic representation of the modulated high frequency waves on a moving photographic film or a strip of paper having a sensitized surface may thus be obtained from the oscillograph and this film may be used as a master record from which photographic prints may be made to form other records.

A short section of a phonograph record formed in this manner is shown in Fig. 3 in which 11 indicates the strip of paper or flexible material forming the record and the curve 15 printed thereon represents the sounds to be reproduced. The curve 15 is in reality a graph of the high frequency oscillations of the oscillator 4 modulated in accordance with the sound waves impressed on the device 1. The envelope of the curve 15 is a graphical representation of the sound waves impinging on the device 1.

Such a record could be reproduced by photo-electric methods or by the use of heat waves instead of light waves transmitted through or reflected from the printing on the record. In the former case a band of light could be directed against the moving record of sufficient width to cover the widest fluctuations of the curve 15. The curve 15 would have the effect of varying the intensity of the band of light in accordance with the modulations of the curve and the intensity of the light after passing through the record would be proportional to the sound waves originally causing the tracing of the curve on the record. Such a band of light of variable intensity could be made to affect a light sensitive cell connected in circuit with a suitable electric or electro-magnetic reproducing system whereby the reproducing system would give a true and accurate reproduction of the sounds originally causing the tracing of the curve on the record.

A modification of the device is shown in Fig. 2 in which the oscillator 4 and device 1 are similar to those in Fig. 1 but in which the oscillograph has been replaced by a recorder 10, the details of which are disclosed in my application, Ser. No. 65,135 filed concurrently herewith. The recorder 10 has a suitable stylus 16 to execute vibrations corresponding to the varying currents impressed on the recorder. This stylus 16 is arranged to rest lightly on a strip 11 of paper or other flexible material which by means of the rollers 12 or other devices is caused to move at a steady rate beneath the stylus. The strip 11 may be provided with an opaque coating of such a nature as to be scraped off by the engraving stylus 16 in its vibrations. The vibrating stylus will thereupon trace a curve

similar to that shown in 15 of Fig. 3 on the record and this record may be used as a master record from which photographic or other replicas may be made.

Instead of forming an opaque coating on the record 11 for use in connection with the system shown in Fig. 2 the surface of the record can be sensitized with any suitable chemical responsive to light. The vibration of the stylus in this case will serve to scratch off the sensitizing material and the record can then be subjected to the action of light rays and developed to obtain the master record from which duplicates may be obtained as before.

While I have described my invention particularly as applied to electrical recording systems, it is quite obvious that it can be carried out by purely optical or mechanical means in which case the markings will be formed on the record either by purely mechanical means or by a traveling beam of light or a band of light of varying width or varying intensity.

I intend to be limited only as indicated by the scope of the following claims:

1. The method of recording sound on a transparent flexible record which consists in providing the record with an opaque coating, and scraping off a portion of the opaque coating by an engraving stylus vibrated at a modulated superaudible frequency.

2. The method of recording sound on a flexible record by means of a mechanically vibrating stylus which consists in providing the record with an opaque coating, vibrating the stylus at a modulated superaudible frequency, and scraping off a portion of the opaque coating by said stylus.

3. The method of recording sound on a flexible record which consists in applying an opaque coating to a master record, scraping off a portion of said coating by an engraving stylus vibrated at a modulated superaudible frequency, and photographing other records by passing light thru the portion of said master record from which the opaque coating was scraped.

4. The method of reproducing sound on a flexible record which consists in providing the record with a light sensitive surface, scratching off a portion of the sensitizing material with an engraving stylus vibrated at a modulated superaudible frequency, and subjecting the record to a developing treatment.

JULIUS WEINBERGER.
